UNITED STATES PATENT OFFICE.

GEORGE B. GRAFTON, OF IRWIN, PENNSYLVANIA, ASSIGNOR TO UNION TOOL COMPANY, OF IRWIN, PENNSYLVANIA, A CORPORATION OF PENNSYLVANIA.

HANDLE.

1,095,851.

Specification of Letters Patent.

Patented May 5, 1914.

Application filed September 16, 1912. Serial No. 720,503.

To all whom it may concern:

Be it known that I, GEORGE B. GRAFTON, a resident of Irwin, in the county of Westmoreland and State of Pennsylvania, have 5 invented certain new and useful Improvements in Handles, of which the following is a specification.

The object of this invention is to provide simple and efficient means for securing a 10 handle to a tool, and has particular reference to a tool which is normally of such form as will afford comparatively little hold for a handle. It is also particularly applicable to tools of slender character, such as 15 miners' needles, which are liable to be distorted or even broken by torsional or twisting strains, the device of the present invention providing such a hold as to distribute the strains and as far as possible prevent 20 breaking.

In the accompanying drawings, Figure 1 is a view in perspective of a portion of a miners' needle and a handle therefor constructed in accordance with the invention, 25 and Fig. 2 is a similar view showing the parts before they are connected together. Fig. 3 is a central longitudinal section. Fig. 4 illustrates a slight modification in the location of the handle on the tool.

30 Referring to the drawings, the tool body 2, which in the present adaptation is a miners' needle, has its extremity 3 bent or disposed at substantially right angles thereto. The handle 4, preferably of grip type, may be 35 formed of malleable iron or steel with the side thereof adjacent the tool grooved or of channel form as indicated at 4'. In the adaptation shown in Figs. 1, 2 and 3 a portion of this channel at one side of the center 40 of the handle is closed to provide a tubular open-end socket 5 which receives the tool extremity 3. Extending outwardly from the end of socket 5 is the socket-like extension 6 provided with the bendable side portions 7, 45 the latter being open or separated as in Figs. 2 and 3 to receive tool body 2, and after the latter is in place parts 7 are bent over the tool, as in Fig. 1, thereby securely fastening the handle.

50 When it is desired to connect the tool and handle at one end of the latter the construc-

tion is as shown in Fig. 4, the socket portions being simply formed at one end of the handle, and in order to take care of the end thrust of the tool the handle end may be 55 provided with a boss 8. In the first described construction the end thrust is borne by handle part 4 intermediate its ends.

The improved connection so unites the tool and handle that the latter cannot work 60 loose nor turn on the tool. Also strains, and particularly twisting or torsional strains, are transmitted to all portions of the tool so that the danger of torsionally distorting the latter, for instance when a miner's needle is 65 stuck in the hole drilled to receive a charge of powder, is eliminated as far as possible. It will be understood, however, that the invention is not confined to miners' needles, being applicable to tools of various kinds. 70

I claim:

1. The combination with a tool formed with a laterally extended extremity, of a handle provided with an open-end socket adapted to receive the tool extremity, the 75 handle formed with flexible parts adjacent to the socket and extending at an angle therefrom to receive therebetween a portion of the tool adjacent the extremity of the latter with said flexible parts bent around 80 the tool for holding it and the handle in assembled relation.

2. The combination with a tool having a laterally extended extremity, of a handle formed with an open-end socket, the handle 85 having part of channel form disposed at an angle to and constituting an open continuation of the socket with the tool entered in said channel and the tool extremity extended into the socket, the handle formed 90 with flexible parts which are bent around the tool for confining the latter and the tool extremity within the channel and within said socket, respectively.

3. The combination of a tool stem formed 95 at its extremity with a right-angle bend, a handle formed with a socket adapted to receive the bent extremity of the stem and also formed with a second socket in communication with and disposed at right angles to the first mentioned socket with the second socket adapted to receive the por- 100

tion of the tool stem adjacent to its bent extremity, the opposite side portions of the second socket adapted to be bent over the tool stem and confine the latter in said second socket and at the same time confine the bent extremity of the tool stem in the first mentioned socket.

In testimony whereof I affix my signature in presence of two witnesses.

GEORGE B. GRAFTON.
